UNITED STATES PATENT OFFICE.

LYMAN S. LEWIS, OF ELKPORT, IOWA, ASSIGNOR OF ONE-HALF TO HARRY B. FITZ-JERRELL, OF ELKPORT, IOWA.

PLOW.

1,018,120.

Specification of Letters Patent. Patented Feb. 20, 1912.

Application filed November 15, 1911. Serial No. 660,429.

To all whom it may concern:

Be it known that I, LYMAN S. LEWIS, a citizen of the United States, residing at Elkport, in the county of Clayton and State 5 of Iowa, have invented a new and useful Plow, of which the following is a specification.

This invention relates to plows, and has for its primary object to provide a novel 10 slip share, wherein the share may be readily removed from the mold board and landside bar and attached thereto.

This invention embodies certain improvements over the structure shown in my 15 former Patent No. 685,813 issued March 7, 1911.

The invention consists of certain novel arrangements and constructions of the various parts as will be hereinafter fully described, the invention being illustrated in the accompanying drawing, wherein:—

Figure 1 is a perspective view of a portion of a plow embodying the present invention, parts being shown in dotted lines 25 and parts broken away. Fig. 2 is a rear elevation thereof. Fig. 3 is a perspective view of the share as removed. Fig. 4 is a fragmental perspective of a detail.

Referring in detail to the drawing, where- 30 in similar reference characters indicate similar parts, the mold board is designated as 1 and a landside bar is designated as 3, the same being usual in plow constructions, and being secured to the plow beam 13, a brace 35 12 being secured at its ends to the beam and the mold board. An angle plate 16 is secured to the forward end of the landside bar 3 and the mold board 1, the said plate having a projecting nose 15. A plate 9 is se- 40 cured to the mold board 1 on the back thereof and has the intermediate portion thereof reduced in width and crimped to form a keeper 11. A heel brace 10 is secured at its ends to the rear end of the landside bar 3 45 and to the rear end of the mold board 1 and has the latter end 4 projecting beyond the lower edge of the mold board.

The share is designated as 7 having the usual landside gunnel 8 and a hook 6 is bent 50 inward from the lower edge of the gunnel. An arm 2, preferably corrugated along its length, is secured to the back of the share 7 and has a tongue 5 struck from the free end thereof and bent back to form an eye, and 55 a lip 18 struck from the inner end of the

arm. A link 14 is pivoted to the arm 2 by means of the tongue 5.

The share in being attached to the mold board and landside bar rests or bears against the forward end of the mold board and the 60 landside gunnel 8 bears against the forward end of the landside bar, the hook 6 engaging over the nose 15 which fits between the share and gunnel and the arm 2 fitting between the angle plate 16 and the projection 4 in the back of the mold board. The projection 4 engages the back of the share 7 and the lip 18 engages over the angle plate 16 and in this manner the share is securely locked to the mold board and landside bar 70 against lateral displacement, and the link 14 is adapted to be swung over the keeper 11 to be engaged thereto. A wedge or cutter pin 17 is insertible into the keeper 11 to securely lock the link 14 in position and retain the 75 share in position. To detach the share, it is therefore only necessary to remove the wedge or cutter pin 17 whereby the link 14 may be disengaged from the keeper 11 to permit the share to be slipped forwardly, the hook 6 80 disengaging from the nose 15 and the arm 2 moving from between the projection 4 and the angle plate 16. In this manner it will be seen that the share may be readily detached and attached to the mold board 85 and landside bar in a convenient, simple and efficient manner.

What is claimed as new is:—

1. In a plow, the combination with a mold board, a landside bar, and an angle plate 90 attached to the mold board and the landside bar and having a projecting nose, of a share having a landside gunnel, and a hook bent inward from the gunnel, the nose of the said plate fitting between the share 95 and the gunnel and engaged by the said hook, and means for connecting the share and mold board.

2. In a plow, the combination with a mold board, a landside bar, an angle plate at- 100 tached to the landside bar and the mold board, and a projection from the mold board, of a share having a landside gunnel, an arm secured to the share fitting between the said projection and flange and having a 105 lip engaging the angle plate, the projection engaging in back of the share, and means for connecting the said arm to the mold board.

3. In a plow, the combination with a mold 110

board, a landside bar, and a keeper secured to the mold board, of a share having a landside gunnel, an arm secured to the share fitting in back of the mold board, a link pivoted to the said arm and engageable over the keeper, and a wedge insertible in the keeper to retain the link in position.

4. In a plow, the combination with a mold board, a landside bar, an angle plate attached to the landside bar and the mold board and having a projecting nose, a projection from the mold board, and a keeper secured to the mold board, of a share having a landside gunnel and a hook bent inward from the gunnel, the nose of the said plate

fitting between the share and gunnel and engaged by the said hook, an arm secured to the share fitting between the said projection and angle plate, the said projection engaging in back of the share, a link pivoted to the said arm and engageable over the said keeper, and a wedge insertible in the keeper to retain the link in position.

In testimony that I claim the foregoing as my own, I have hereto affixed my signature
